United States Patent Office.

WILLIAM H. COLEMAN, OF NEW ORLEANS, LOUISIANA.

Letters Patent No. 95,325, dated September 28, 1869.

IMPROVEMENT IN VELOCIPED.

The Schedule referred to in these Letters Patent and making part of the same.

To all whom it may concern:

Be it known that I, WILLIAM H. COLEMAN, of the city of New Orleans, State of Louisiana, have invented a certain new and useful Improvement in Velocipedes; and I do hereby declare the following to be a full, clear, and exact description of the same, reference being had to the annexed drawing, making a part of this specification.

The object of my invention is to diminish the power required to propel a velocipede of any given-sized wheels, to provide for an increase of the diameter of the driving-wheels beyond what is possible when the rider propels the machine by cranks directly connected with the axle of the said wheel, and to diminish the power required to propel any given velocipede at any given rate of speed; and

It consists of a mechanical arrangement through the agency of which the rider is enabled to apply an enormous lever-power to rotate the driving-wheel, first with one foot and then with the other, in the same alternate manner as when the machine is driven in the usual manner by pedals or cranks connected with the axis of the driving-wheel, without any appreciable increase of friction from the intermediate gearing I employ, in order to obtain the said lever-power.

My arrangement is susceptible of such modification that I may use a complete power-wheel that rotates continuously, or only a segment of a wheel which vibrates within prescribed limits, or which makes a partial revolution, first in one and then in the reverse direction, accordingly as it is acting as the medium to communicate power, or is returning to its first position to renew such operation.

But my invention will be better understood by referring to the drawing, which shows it in both the forms in which it can be arranged.

In order to apply my invention to a velocipede, I provide, on each side of the driving-wheel A, a circular recess, B, in which three or more pawl-notches or clutches *a* are cut into the hub C, in such manner that pressure from a pawl, to be hereafter described, will rotate the said wheel so as to carry the velocipede forward, and also so that each of said clutches on each of the opposite sides of the wheel will occupy a relation which will be midway between that and the two that are next to it, on each side of it, in order that the pawls respectively connected therewith may come alternately into action, and thus rotate the said driving-wheel continuously.

On the axle, on each side of the hub, to which it will be understood the axle is permanently and immovably fixed, driving-pinions D, only one of which is shown on the drawing, are fitted in such manner that they will readily revolve thereupon, and on each inner side of these pinions a circular projecting part, E, is provided, which fits into the circular recesses B.

To this projecting part or sleeve one or more pawls *b* are secured, in recesses that are sunk in its perimeter, in such manner as not to interfere with the easy rotation of the pinions D in one direction, while preventing its rotation in the other by the impingement of their points against the clutches *a*, without, at the same time, rotating the driving-wheel A.

Outside the pinions D, the two legs of an ordinary bifurcated standard, F, are secured on the axle of the driving-wheel A, in the usual way, to which the bar G is attached, to connect the hind wheel H with said driving-wheel, and support the rider's seat I, as in the case of all two-wheel velocipedes.

To the standard F, just below the point of its connection with bar G, is also secured a curved bar, J, that extends down to a point at or near a line drawn between the axes of the driving-wheel A and hind wheel H, and is terminated by a circular expansion, through which an aperture is made to receive the axis of a power cog-wheel, K, or power-segment of a wheel, L, the first being shown on the drawing by deeper shading at the rear of the latter, which overlaps and conceals the front half of the former, and is, moreover, distinguished by lighter lines of shading.

Outside of the power-wheels K, or power-segments L, accordingly as the one or the other may be used, bars M connect the axis of the same with the axis of the driving-wheel A, in such manner as not to interfere with the easy rotation of the said wheels when the velocipede is in motion, and so as to reinforce and sustain the bars J at the same time.

The wheels K, or segments L, as the case may be, gear into the pinions D, so that when motion is given the former it is communicated to the latter, and through the action of the pawls *b*, against the clutches *a*, from the latter to the driving-wheel A also.

When the wheels K are employed, the means for actuating them consist of two levers N, which, articulating on the axis of said wheels, independently of and extending rearward considerably beyond the perimeter of the same, constitute powerful pedal-levers for the feet of the rider, and, by extending from the axis of the same frontward, and at an inclination upward, as shown, they provide a means also for establishing a connection with the bars M, through the helical springs O, which maintain them in proper position for operating the machine, whenever they are not forced out of such position by the foot of the rider, and brings them back into this position whenever the pressure of the foot of the rider is removed from off them.

The rear or pedal extremities of the lever N, when used in connection with the wheels K, are provided with pawls *d*, which are so arranged that whenever these extremities are forced down by the rider's feet, they will take into the cogs of the power-wheels K, and force those wheels to rotate to the extent of the

downward sweep of said extremities, at the points at which they (the pawls) are attached thereto, and insomuch as the two levers are alternately operated, it follows that continuous rotation is imparted to the said power-wheel, and through the intermediate gearing to the velocipede itself.

When segments L are used instead of wheels K, the mechanism is the same I have just described, except that the lever N is firmly secured to said segment, and cannot be moved independently thereof, and that no pawls d are used, because, instead of rotating, the segments vibrate within given limits, as they are alternately pressed down to drive the machine forward by the rider's feet, and thrown back into proper position for another impulsion by the springs O, which I neglected to state at the proper place, subserve the same purpose when the wheels K are used.

The extent of the levers N beyond the perimeter of the power-wheel, or the length of the radius of the power-segment, necessarily gives me an increase of power for propelling the machine, which is precisely proportionate to the excess of length of the levers over the semi-diameter of the wheel, or the radius of the segment less, of course, the loss resulting from the friction of the intermediate parts, which is almost inappreciable; and insomuch as that power is always

necessarily beyond what is possible when the pedals are connected directly to cranks on the axis of the driving-wheel, and may go very far beyond, it is obvious the machine may be driven with less muscular exertion, and at a much higher rate of speed than can be attained by a direct pedal attachment to the driving-wheel.

Instead of using the ordinary cross-arm for guiding my velocipede, I employ an arm, P, extending toward the rear of the machine, to which I affix a handle, R, which I find a far more convenient arrangement.

Having thus described my invention,

What I claim, and desire to secure by Letters Patent, is—

The wheels K, or their equivalents, the segments L, the levers N, pawls d, and springs O, in combination with the loose driving-pinions D, when the latter are provided with projections E, fitting into recesses in the hub of the driving-wheel A of a velocipede, pawls b to take into clutches a, and all the parts are constructed, arranged, and operate substantially as described, for the purpose set forth.

WM. H. COLEMAN.
